UNITED STATES PATENT OFFICE.

ADOLPH F. HAMACEK, OF CHICAGO, ILLINOIS, ASSIGNOR OF ONE-HALF TO D. B. BAKER, OF CHICAGO, ILLINOIS.

MOVING-PICTURE MACHINE.

No. 909,404.

Specification of Letters Patent.

Patented Jan. 12, 1909.

Application filed June 24, 1908. Serial No. 440,080.

To all whom it may concern:

Be it known that I, ADOLPH F. HAMACEK, a citizen of the United States, residing at Chicago, in the county of Cook and State of Illinois, have invented a new and useful Improvement in Moving-Picture Machines, of which the following is a specification.

My invention relates to improvements in the class of machines for exhibiting or projecting and taking pictures on an intermittently moving picture-film; and it relates particularly to improved mechanism for producing the intermittent motion of the film past the lens and to improved mechanism for feeding the film by friction in contradistinction to positively feeding the same through the medium of sprocket-teeth engaging perforations in the film-edges. As is well known in the art, the so-called movement ordinarily used for producing the required intermittent motion of the film, and consisting of a form of Geneva-gear, is more or less unsatisfactory inasmuch as it exerts a jerking action on the film in starting it, tending to its injury; and the sprocket-feed of the film is also objectionable because the sprocket-teeth in withdrawing from the edge-perforations in the film unavoidably vibrate it with the result of blurring the pictures either in taking or projecting them. Moreover, the sprocket-teeth tend to tear or strip the edge-perforations since that species of feed must be at the rate of a definite number of pictures for a given brief period, and any disorganization of the relation of the perforations to the sprocket-teeth impairs the proper registration of the pictures with the lens. Such disorganization is caused by variation of the length of the film by shrinkage in its development or from age, causing hastening of the feed, or by elongation thereof under some conditions, causing retardation in the feed. I overcome these and other objections by a novel construction of friction-feed for the film and a novel construction of means for producing its required intermittent movement, either of these devices being capable of use with any suitable construction of the other, though when used together in the same machine they produce the best result by co-operating in causing desired uniformity and smoothness of travel of the film.

In the accompanying drawings, Figure 1 is a view in side elevation, partly broken, of a moving-picture machine provided with my

improvements; Fig. 2 is a similar view of the same presenting the opposite side; Fig. 3 is a section on line A, Fig. 1; Fig. 4 is a section on line B, Fig. 5, with the cover of the shutter-mechanism removed; Fig. 5 is a section on line C, Fig. 3; Fig. 6 is an enlarged vertical section through the frictional film-feeding device on line D, Fig. 3; Fig. 7 is a broken view in side elevation of the rotary wheel of the friction-feed device; Fig. 8 is a section on line E, Fig. 6; Fig. 9 shows the setting means for the expandable and contractible feed-wheel by a plan view; and Fig. 10 is a detail view of a loop-forming adjunct for the film.

In a suitable casing 10, shown of rectangular form, and near the front end containing an opening 11, is mounted a vertical frame 12 carrying the lens-barrel 13 coincident with the opening 11. On the inner face of the frame is provided the usual hinged spring clamping-frame 14 for tautening the picture-film 15 in its travel across the inner end of the lens-barrel, the open rear end of which is covered by a hood 16 containing a spring-pressed longitudinally open follower 17 preferably of soft wood to insure exclusion of light from the film about the picture and supported on the end of a telescoping tube 18 sustained on the frame through which to direct the light, the telescoping construction of the tube, which affords means through which to inspect the film for focusing the pictures, adapting the hood to be retracted to facilitate access to the lenses, film and clamping-frame for purposes of adjustment. The opening through the follower is of the exact area of each picture on the film and thus prevents spreading of the light beyond the area of the picture. The picture-film 15 is in a coil journaled in a compartment 19 in the casing, out of which it passes, at 20, under a guide-roller 21 about a guide-roller 22 journaled on the frame 12 above the clamping-frame between which and the lens-barrel it is fed intermittently; and it is wound upon a take-up roll 23 in a compartment 24 in the casing, which it enters at 25, being guided therein by a roller 26.

None of the elements thus far described, except the hood-device, present any important features of novelty, being in common use in moving-picture machines.

On the edge of the upright frame 12 near one side of the casing is journaled a large gear-wheel 27 with a grooved pulley 28 on its

outer face geared by an endless belt 29 to a smaller pulley 30 on the shaft 31 which carries the take-up coil of film in the compartment 24. For operating the machine a 5 crank 33 is shown to be applied to the pulley 28, though it may be operated by any suitable motor.

In bearings on the outer side of the frame 12 is journaled a shaft 34 carrying a pinion 10 35 in mesh with the gear 27 and a miter-gear 36 meshing with a similar miter 37 on a shaft 38 journaled in bearings at opposite sides of the frame through which it passes. The shaft 38, which extends at a right-angle to 15 the shaft 34, carries a balance-wheel 39 and the driving member of a device, hereinafter described, for actuating the picture-film by an intermittent movement, the driven member 20 of this device being on a shaft 40 journaled in suitable bearings to extend at a right-angle to and beneath the shaft 38 and carrying the drum or wheel of the frictional film-feeding device, hereinafter described.

The device for producing intermittent rotary motion forms the subject of my pending application Serial Number 433,356, filed May 18, 1908. It comprises the driving member 25 41 and the driven member 42. The driven member is a cog-wheel having outwardly tapering teeth formed to extend parallel with the axis of rotation with each tooth beveled from near the circumferential center of the wheel toward one face thereof to extend inclinedly to the remainder of the tooth. The 30 driving member is formed of teeth 43 and 44 extending, at intervals apart corresponding with those of the member 42, partway—say approximately two-thirds—about the circumference of a sleeve or enlargement 45 on 40 the shaft 38, the ends of successive ones of these teeth being joined by similar worm-sections 46 extending about the remaining portion of said circumference. The end-portions of each worm-section extend at a right-angle 45 to the axis of rotation of the driving member and its intermediate curved portion describes a somewhat steep inclination between said end-portions. The teeth 43 are blunt-faced with beveled edges and are adapted to mesh 50 with the teeth of the driven member to hold the latter against rotation, while the tooth 44 is pointed and of greater diameter than the teeth 43 to extend deeply between the teeth of the driven member and afford a locking tooth therefor against vibration or "back-lash".

The frictional feed-device comprises the drum or wheel 47 of peculiar construction to render it expandable and contractible, and a 55 spring-pressed multiple-roller device 48 coöperating therewith. The wheel comprises a spider-like center on the shaft 40, having radial arms 49 arranged in pairs forming spaces between them to receive and confine adjustably the metal-stems 50 of arc-shaped heads

51 provided with inclinedly-inturned edge-flanges 52. The heads 51 are covered with sections 53, of hard material preferably hardened leather, meeting at their ends, adjacent to which they are bent to produce inturned 70 flanges 54 fitting against the faces of opposing flanges 52, where each leather flange is secured against a face of a flange 52 by a metal strip 55 fastened in place by a countersunk screw 56 passed transversely through the flanges 52 and 54 and plate 55. The leather sections 53 are cut away or countersunk between their lateral edges to form a circumferential recess or groove 57 about the wheel in which it is surrounded by a suitable band-spring 58, preferably in the form of a thin split band of spring steel tending to contract the wheel when expanded, as and for the purpose hereinafter described, between the circular edge-flanges 59 about the wheel formed by its annular end-heads 60. A sleeve 61 surrounds the shaft 40 (Fig. 6) to rotate with it, and carries a head 62 from which similar wedge-shaped keys 63, of which six are used in the present construction, extend along the 90 sleeve through the central openings in the wheel-heads 60, each key passing through the base-portion of a space between a pair of arms 49, whereby when the keys are advanced through the wheel their wedging engagement with the inner ends of the stems 50 forces the latter outwardly to expand the periphery of the wheel between the flanges 59, and retracting the keys permits that periphery to contract under the pressure of the 100 spring 58. To thus work the keys the circular head 62 is circumferentially recessed to receive a split collar 163 clamped about it and pivotally confined by pins 64 in a rectangular yoke 65, which has bearing at a ball 66, 105 extending from one end, in the frame 12 and is provided on its opposite end with a handle 67 carrying a spring-pressed pivotal finger 68 curved at its forward end where it bears against the upper surface of a rigid segmental 110 plate 69 to engage the same frictionally for holding the keys 63 in any position to which they are adjusted in expanding the feed-wheel.

To coöperate with the wheel 47 in feeding 115 the picture-film a series of friction-rollers is provided in a structure involving, by preference, the following-described parts: An arc-shaped trough 70, forming a roller-frame, the upper edges of the sides of which conform to 120 the edges of the wheel-flanges 59, has its base provided with openings at uniform intervals apart. At one end this trough is suspended at a transverse rod 71 (Fig. 5) by a pivotal hook 72 from a support 73 extending from 125 the frame 12, and it carries on its opposite end a bail 74 at which it is resiliently suspended by a spiral spring 75 from the extension of the frame 12 in which one end of the movement-shaft 38 is journaled. Lugs 76 130

extend at intervals outwardly and radially from the trough-base and have rigidly fastened to their outer ends an arc-shaped bearing-strip 77. Coincidentally with the openings 5 in the base of the trough the sides thereof are provided with rectangular radial slots 78, extending short of the inner or upper edges of the sides, and in each pair of these slots fit the arms of a rectangular yoke 79 having a stem 80 extending from its base loosely through the plate 77 and surrounded by a spiral-spring 81 confined between the plate and yoke-base to support the yoke resiliently; and in each pair of yoke-arms is 15 journaled a roller 82 to bear at enlargements or bands 182 about its ends (Fig. 6) against the periphery of the wheel 47 at the sides of the recess 57 in the leather sections 53 forming it.

20 The shutter 83 shown (Fig. 4) is in the form of a counterbalanced disk with a segment removed to produce the light-admitting opening 84. It is centrally supported between the frame 12 and adjacent end of the 25 casing 10 in a compartment in the latter to turn past the inner end of the lens-barrel, on a shaft 85 journaled in a bearing in said frame adjacent to the clamping-gate 14 and carrying on its inner end a beveled pinion 86 30 meshing with the teeth about the face of a beveled gear 87 on one end of a shaft 88 journaled in bearings extending from the inner face of the frame 12 and carrying on its opposite end a gear-wheel 89 meshing with the 35 upper part of the master-gear 27.

The film 15 in its course from the coil in compartment 19 to the take-up roll in compartment 24 passes about the wheel 47, between the guide-flanges 59 thereof and bears 40 only against the raised parts 53 of its periphery to avoid marring the face of the film, and the raised end-portions 182 of the plurality of spring-pressed rollers 82 clamp the edge-portions of the film against the wheel-parts 53 to bear against it uniformly throughout a considerable extent of its length, and thereby distribute the pressure over such area with the advantage of enabling the pressure of each roller to be so light as to avoid 50 injury to the film in their feeding co-operation with the wheel, and that of producing a regular, smooth, positive and even feed of the picture-film.

The operation is as follows: Rotation of 55 the gear 27, as by turning the crank 33, by its gear-connection with the shaft 38 (Fig. 3) rapidly rotates the latter and with it the hub 45, throughout part of the rotation of which its worm-sections engage the beveled parts 60 of the teeth of the driven-member 42 to drive it, first with a relatively slow movement, then advancing to a rapid movement, and then receding to the same slow movement, by reason of the described relation of the 65 straight-end and curved intermediate por-

tions of the worm-sections, thereby actuating the driven member from no motion to a slow motion, increasing to a rapid motion, then gradually to the slow motion terminating in no motion. Throughout the remainder of 70 the rotation of the driving member its teeth engage with the straight parts of the teeth of the member 42, the shorter teeth 43 holding the latter against further rotation until they are again engaged by the worm-sections, and the pointed tooth 44 locking the driven member, by the close fit between its teeth, against vibration or "back-lash". The member 42 is thus driven by an intermittent motion and since it is on the same shaft with the wheel 47 80 the latter is driven correspondingly to feed the film intermittently past the opening 11 to be taken up by the roll 23 in its rotation, through the belt-connection 29 with the pulley 28. The driving connection of the master-gear 28 with the shutter-shaft 85 is so timed as to admit light through the lens-barrel at the proper intervals, as usual, in harmony with the operation of the intermittent-motion device. 90

Improper registration of the picture-sections on the film with the opening 11 may be readily corrected by the operator by turning the handle 67 to effect expansion or contraction of the wheel 47, thus by advancing the 95 keys 63 to spread the wheel-sections apart or by retracting them to permit the spring 58 to contract them, thereby, in the one instance, increasing the circumference of the wheel to produce faster feeding of the film, if that be 100 the correction required, and, in the other instance, diminishing the circumference to slower feeding of the film if that be the correction required. To effect these adjustments of the feed, which may be produced 105 with extreme nicety under the inspection of the operator, he merely grasps the handle 67 to release the finger 68 and permit the yoke 65 to be turned freely, and when he has attained the desired degree of adjustment it is 110 retained by engagement of the finger 68 with the plate 69 upon releasing the grip on the handle.

Where the coil of film in the compartment 19 is of large size, or heavy, the resistance of 115 its inertia in starting it would tend to injure it, by straining or even tearing it under the operation of the intermittent-motion device. To counteract this tendency, the device may be provided which is illustrated in Fig. 10. 120 It consists of a spring-arm 90 extending from the frame 12 to bear a roller 91 on its free end against the film between the guide-rollers 21 and 22. By this provision the pressure of the arm forms a loop in the film 125 against which the action of the intermittent-motion device is exerted, thereby taking the strain of starting off the coil and requiring the said device to overcome merely the comparatively light resistance of the spring-arm 130

41
90 in producing the paying out of the film from the coil.

What I claim as new and desire to secure by Letters Patent is—

- 5 1. In a moving-picture machine, the combination with a frictional film-feeding device, of an intermittent-motion device in driving engagement with said feeding-device and comprising a rotary toothed wheel forming 70 the driven member and a driving member 10 consisting of a rotary shaft having gear-teeth and a pointed locking-tooth of greater diameter than said gear-teeth extending about one portion of its circumference and 15 worm-sections extending about another portion of its circumference to successively engage said teeth and worm-sections of the driving-member with the teeth of the driven-member, for the purpose set forth.
- 20 2. In a moving-picture machine, the combination with an intermittent-motion device, of a frictional film-feeding device, comprising an expansible and contractible wheel in 25 driven engagement with said intermittent-motion device, means for expanding said wheel simultaneously and uniformly throughout its periphery, and a plurality of rollers 30 coöperating with said wheel, for the purpose set forth.
- 30 3. In a moving-picture machine, the combination with an intermittent-motion device, of a frictional film-feeding device comprising an expansible and contractible wheel in driven engagement with said intermittent-motion device and having an unyielding peripheral surface, means for expanding and means for contracting said wheel simultaneously and uniformly throughout its periphery, and a plurality of rollers 35 coöperating with said wheel, for the purpose set forth.
- 40 4. In a moving-picture machine, the combination with an intermittent - motion device, of a frictional film-feeding device comprising a wheel in driven engagement with said intermittent-motion device and having an expansible and contractible periphery formed of sections, wedging-keys for forcing out the sections to expand said periphery, 45 and a plurality of rollers coöperating with said periphery, for the purpose set forth.
- 50 5. In a moving-picture machine, the combination with an intermittent-motion device, of a frictional film-feeding device comprising a wheel in driven engagement with said intermittent-motion device and having an expansible and contractible periphery formed of sections, a spring-band around 55 said periphery, wedging-keys for forcing out the sections to expand the periphery against the resistance of said band, and a plurality of rollers coöperating with said periphery, for the purpose set forth.
- 60 6. In a moving-picture machine, the combination with an intermittent-motion de- 65 vice including a driven member on a rotary shaft, of a frictional film-feeding device consisting of a wheel on said shaft comprising a center having pairs of radially-extending arms forming spaces between them, stems recipro- 70 cally confined in said spaces and terminating in arc-shaped heads, and spring-pressed sections of yielding material, as leather, confined against said head to form the periphery of the wheel, a head on said shaft carrying wedge-keys working through the wheel against the inner ends of said stems, and a plurality of rollers coöperating with said periphery, for the purpose set forth.
7. In a moving-picture machine, the combination with an intermittent-motion device including a driven member on a rotary shaft, of a frictional film-feeding device consisting of a wheel on said shaft comprising a center 85 having pairs of radially-extending arms forming spaces between them, stems recipro- 80 cally confined in said spaces and terminating in arc-shaped heads, sections of yielding material, as leather, confined against said heads to form the periphery of the wheel and countersunk between their edges to form a recess about the periphery, and a spring-band in 90 said recess, a head on said shaft carrying wedge-keys working through the wheel 95 against the inner ends of said stems, and a plurality of rollers coöperating with said periphery, for the purpose set forth.
8. In a moving-picture machine, the combination with an intermittent-motion device 100 including a driven member on a rotary shaft, of a frictional film-feeding device consisting of a wheel on said shaft comprising a center having pairs of radially-extending arms forming spaces between them, stems recipro- 105 cally confined in said spaces and terminating in arc-shaped heads, and spring-pressed sections of yielding material, as leather, confined against said head to form the periphery of the wheel, a head on said shaft carrying wedge-keys working through the wheel against the inner ends of said stems, a yoke pivotally connected with said head and pivotally supported at one end in the machine-frame, and a handle on the opposite 110 end of the yoke provided with means for releasably holding it in adjusted position, for the purpose set forth.
9. In a moving-picture machine, the combination with an intermittent-motion device 120 including a driven member on a rotary shaft, of a frictional film-feeding device consisting of a wheel on said shaft comprising a center having pairs of radially - extending arms forming spaces between them, stems recipro- 125 cally confined in said spaces and terminating in arc-shaped flanged heads, and spring-pressed sections of yielding material, as leather, covering said heads and secured to the flanges thereof to form the periphery 130

of the wheel, the head on said shaft carrying wedge-keys working through the wheel against the inner ends of said stems, and a plurality of rollers coöperating with said 5 periphery, for the purpose set forth.

10. In a moving - picture machine, the combination with an intermittent-motion device including a driven member on a rotary shaft, of a frictional film-feeding device comprising an expansible and contractible wheel on said shaft provided with means for expanding and means for contracting it, and an arc-shaped series of spring-pressed rollers supported to coöperate with the periphery 15 of said wheel, for the purpose set forth.

11. In a moving - picture machine, the combination with an intermittent-motion device including a driven member on a rotary shaft, of a frictional film-feeding device 20 comprising an expansible and contractible wheel on said shaft provided with means for expanding and means for contracting it, and a resiliently suspended arc-shaped trough carrying spring-pressed reciprocating yokes

with rollers journaled therein to coöperate 25 with the periphery of said wheel, for the purpose set forth.

12. In a moving - picture machine, the combination with a shutter in a compartment and a lens-barrel with which said shutter 30 coöperates, of a light-tube in the casing, a light excluding hood on one end of said tube covering the inner end of the lens-barrel, and a spring-pressed hollow follower in said hood, for the purpose set forth. 35

13. In a moving - picture machine, the combination with the shutter in a compartment in the casing and the lens-barrel with which said shutter coöperates, of a telescoping light-tube in the casing, a hood on an end 40 of said tube covering the inner end of the lens-barrel, and a spring-pressed hollow follower in said hood, for the purpose set forth.

ADOLPH F. HAMACEK.
